US0D1083032S

(12) **United States Design Patent** (10) Patent No.: **US D1,083,032 S**
 Svendsen et al. (45) Date of Patent: ** Jul. 8, 2025

(54) **NOZZLE**

- (71) Applicant: **Melnor, Inc.**, Winchester, VA (US)
 (72) Inventors: **Sean Wesley Svendsen**, Columbus, OH (US); **Donald Collins Meves**, Columbus, OH (US); **Eric James Fickas**, Plain City, OH (US)
 (73) Assignee: **Melnor Inc.**, Winchester, VA (US)
 (***) Term: **15 Years**
 (21) Appl. No.: **29/904,430**
 (22) Filed: **Oct. 6, 2023**

Related U.S. Application Data

- (62) Division of application No. 29/800,848, filed on Jul. 23, 2021, now Pat. No. Des. 1,007,648, which is a division of application No. 29/718,888, filed on Dec. 30, 2019, now Pat. No. Des. 928,287, which is a division of application No. 29/670,354, filed on Nov. 15, 2018, now Pat. No. Des. 874,612, which is a division of application No. 29/598,175, filed on Mar. 23, 2017, now Pat. No. Des. 839,992.

I can't find a decent garden hose nozzle, posted garagejournal.com. Available Date: Feb. 25, 2011 [site visited Dec. 6, 2024] Available: <<https://www.garagejournal.com/forum/threads/i-cant-find-a-decent-garden-hose-nozzle.92984/page-3>> (Year: 2011).*

Primary Examiner — Kevin K Rudzinski(74) *Attorney, Agent, or Firm* — HEA LAW PLLC;
 Darrin A. Auito(57) **CLAIM**

The ornamental design for a nozzle, as shown and described.

DESCRIPTION

FIG. 1 is a rear perspective view of nozzle, showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a front perspective view thereof.
